UNITED STATES PATENT OFFICE.

JOSEPH E. SHOENBERG, OF NEW YORK, N. Y.

DESIGN FOR A RAIN-COAT AND SHELTER-TENT.

SPECIFICATION forming part of Design No. 29,651, dated November 8, 1898.

Application filed May 26, 1898. Serial No. 681,744. Term of patent 3½ years.

To all whom it may concern:

Be it known that I, JOSEPH E. SHOENBERG, a citizen of the United States, residing at the city of New York, in the county and State of New York, have invented and produced a new and original Design for a Rain-Coat and Shelter-Tent, of which the following is a specification, reference being had to the accompanying drawings, forming part thereof, and showing a rain-coat and shelter-tent embodying my design.

The leading features of my design consist in the shape of the article and the form of the pockets therein.

In the accompanying drawings, forming part of this specification, wherein like letters of reference indicate like parts, Figure 1 is a face or plan view of a rain-coat and shelter-tent embodying my design, and Fig. 2 is a section taken on the line 2 2 of Fig. 1.

In said drawings, A designates the rain-coat and shelter-tent, describing in outline a parallelogram having a border B along its edges, and C C denote triangular pockets arranged adjacent to the upper corners of said rain-coat and shelter-tent within the outline described by the border B.

I claim—

The design for a rain-coat and shelter-tent, substantially as herein shown and described.

Signed at the city of New York, in the county and State of New York, this 24th day of May, 1898.

JOSEPH E. SHOENBERG.
